D99-11

AU 291

EX

OR D 6,595

DESIGN.

N. HAYDEN.

Coffin-Handles.

No. 6,595.

Patented April 22, 1873.

Fig. 1.

Fig. 2.

Witnesses:

Desquidio
Alex F. Roberts

Inventor:

N. Hayden
Per Miner H

UNITED STATES PATENT OFFICE.

NEHEMIAH HAYDEN, OF ESSEX, CONNECTICUT.

DESIGN FOR COFFIN-HANDLES.

Specification forming part of Design No. 6,595, dated April 22, 1873; application filed April 12, 1873.

To all whom it may concern:

Be it known that I, NEHEMIAH HAYDEN, of Essex, in the county of Middlesex and State of Connecticut, have invented a new and original Design for Coffin-Handle Ears, of which the following is a specification:

Figure 1 is a photographic view of a coffin-handle, illustrating my design. Fig. 2 is a photographic view, showing the design applied in a different way.

Similar letters of reference indicate corresponding parts.

My invention has for its object to furnish a neat and appropriate design for the ears of coffin-handles.

The invention consists in a Roman cross, having a figure extended upon it, and surrounded at its lower part by the figures of two or more women, as a design for coffin-handle ears, as hereinafter fully described; and in a Grecian cross, placed at the foot of a Roman cross, which has a figure extended upon it, and is surrounded at its lower part by the figures of two or more women, as a design for coffin-handle ears, as hereinafter fully described.

The outline of the ears A may be of any desired form, and their edges may be left plain, as shown in Fig. 2, or may be provided with an ornamental border, as shown in Fig. 1. In the middle and upper part of the ear is represented, in raised work, a Roman cross, having a figure extended upon it, thus representing the crucifixion of Christ. Surrounding the lower part of the cross are represented, also in raised work, two or three figures of women. The lower part of the ear, where the arm of the handle is pivoted, may have a Grecian cross formed upon it, as shown in Fig. 1, which Grecian cross may be surrounded with ornamental work; or, if desired, the Grecian cross may be omitted and the lower part of the ear otherwise ornamented, as shown in Fig. 2.

I claim as my invention—

1. A Roman cross having a figure extended upon it representing the crucifixion of Christ, and surrounded at its lower part by the figures of two or more women, as a design for coffin-handle ears, substantially as herein shown and described.

2. A Grecian cross placed at the foot of a Roman cross, which has a figure extended upon it representing the crucifixion of Christ, and is surrounded at its lower part by the figures of two or more women, as a design for coffin-handle ears, substantially as herein shown and described.

NEHEMIAH HAYDEN.

Witnesses:

JAMES T. GRAHAM,
ALEX. F. ROBERTS.